UNITED STATES PATENT OFFICE.

ELBERON D. SMITH, OF BROOKLYN, NEW YORK, ASSIGNOR TO AMERICAN MACHINE & FOUNDEY COMPANY, OF NEW YORK, N. Y., A CORPORATION OF NEW JERSEY.

PASTING MECHANISM FOR CIGARETTE-MACHINES.

1,075,272.

Specification of Letters Patent.

Patented Oct. 7, 1913.

Application filed August 19, 1912. Serial No. 715,715.

To all whom it may concern:

Be it known that I, ELBERON D. SMITH, a citizen of the United States, residing at Brooklyn, county of Kings, and State of New York, have invented a new and useful Improvement in Pasting Mechanism for Cigarette-Machines, of which the following is a specification.

This invention relates to an improvement in pasting mechanisms for cigarette machines, particularly for high speed machines of the continuous rod type.

In the operation of high speed cigarette machines of the continuous rod type, it has been found that more or less frequent adjustment of the pasting mechanism with respect to the cigarette rod forming mechanism is necessary. This is partly due to variations in the paper forming the wrapper of the cigarette rod, partly to the condition of the tobacco of which the cigarette filler is formed, which varies with varying atmospheric conditions, and partly to variations in the tobacco feed whether manually or automatically effected. Heretofore, in the operation of such machines, it has been necessary to stop the machines in order to make the necessary adjustment. This results in loss of time and decrease in the production of cigarettes by the machine.

The present invention has for one of its objects the production of a pasting mechanism which may be adjusted with respect to the cigarette rod forming mechanism while the machine as a whole is in operation, thus avoiding the necessity for stopping the machine and the consequent decrease in production of cigarettes by the machine.

A further object is the production of a device of the character mentioned which may readily be thrown in and out of operative position to enable the operator to effect a saving of time and a consequent increase in the production of cigarettes by the machine whenever it is necessary to lead the wrapper paper through the cigarette rod forming mechanism, as for instance when the machine is started, and whenever the paper breaks or tears, as it sometimes does.

With these and other objects not specifically mentioned in view, the invention consists in certain constructions, combinations, improvements and parts which will be hereinafter fully described and then specifically set forth in the claims hereunto appended.

In the accompanying drawings which form a part of this specification and in which like characters of reference indicate the same or like parts, Figure 1 is a plan view, partly broken away, of a device constructed in accordance with the invention. Fig. 2 is a cross-sectional view not taken on a straight line across Fig. 1, but taken on a broken line to clearly bring out the structure of the driving mechanism for the device illustrated in Fig. 1; and Fig. 3 is a front elevation of a part of the device shown in Figs. 1 and 2, the cigarette rod forming mechanism being omitted in the interest of clearness.

In carrying the invention into effect, there is provided a cigarette rod forming mechanism which may be of any of the types well known in the art, and since the particular construction of such mechanisms is not necessary to a full understanding of the present invention, only a fragmentary portion of a cigarette rod forming mechanism is shown in the drawings. The cigarette rod forming mechanism, however, will in any case include a channeled plate marked 1, through which the cigarette rod 2 passes. As shown, the plate 1 is supported by a bracket 3 suitably supported upon the bed 4 of a cigarette machine. In all the machines of the continuous rod type known in the art, the paper wrapper for the cigarette, as it passes the pasting mechanism, has one side upstanding as at 5 and to which the paste is applied.

For the purpose of enabling an operator to lead the cigarette wrapper through the rod forming mechanism, there is provided a pasting mechanism which may be readily and quickly swung out of operative position with respect to the cigarette rod forming mechanism to clear the same of obstructions, and the particular mounting of this pasting mechanism may be varied within wide limits. The driving means for the pasting mechanism may also be varied within wide limits.

In the device selected to illustrate the invention, there is provided a vertical rotating shaft 6 suitably journaled in a bush 7 fixed in a block 8 countersunk in the bed 4 of the cigarette machine. This rotating shaft, when used, may derive its motion from any suitable source of motion. As shown, its lower end is provided with a pinion 9 in mesh with a gear 10, which gear

is formed integral with a worm wheel 11. The gear 10 and worm wheel 11 are journaled upon a post 12 stationarily mounted in a bush 13 secured to the lower part of the bed 4 before referred to. The worm wheel 11 is in mesh with a worm 14 which is fixed upon a shaft 15. The shaft 15 is or may be one of the main power shafts of the cigarette machine in connection with which the device is used. There is further provided a bracket 16 swingably mounted upon the upper end of the vertical shaft 6 before referred to. This bracket is provided with an integral plate 17 to which a paste pot 18, of well-known construction, is secured by means of thumb screws 19-19. The paste pot is provided with a feed wheel 20 and with a doctor 21 of well-known construction and which may be readily adjusted with respect to the feed wheel 20 by means of an adjusting screw 22. The pasting mechanism is further provided with a paste applying wheel or disk 23 which contacts with the feed wheel 20 and takes paste therefrom and transfers it to the upstanding part of the paper wrapper for the cigarette rod at 5. This paste applying wheel 23 is fixed upon a shaft 24 mounted in cone bearings 25-26. The lower bearing 25 is fixed, but the upper bearing 26 is adjustable by means of a screw 27 and thumb lock nut 28. The bearings 25 and 26 are carried in a yoke 29 which is clamped at 30 to a post 31 mounted in a hub 32 projecting from the bracket 16 before referred to. The upper end of the shaft 24 is provided with a pulley 33, over which runs a driving belt 34 which derives its motion from any suitable moving part of the cigarette machine as a whole, but which is not shown. The feed wheel 20 is mounted upon a shaft 35 suitably journaled in bearings formed in the bracket 16 before referred to. One end of the shaft 35 carries a bevel gear 36 which is in mesh with a bevel gear 37 fast upon the upper end of the vertical rotating shaft 6 before referred to. It will be readily understood that the rotating shaft 6, the pulley 33 and the belt 34 constitute driving means for the pasting mechanism, and it is to be understood that in certain constructions within the invention, different driving mechanisms may be employed.

Means are provided for adjusting the pasting mechanism with respect to the cigarette rod forming mechanism, and this means may vary in construction within wide limits. In the best constructions provision is made to adjust the pasting mechanism in two directions; that is, toward or away from the upstanding wrapper paper and along said paper toward or away from the edge thereof.

In the device selected to illustrate the invention, a vertical adjustment of the past-

ing mechanism with respect to the cigarette rod forming mechanism is effected by the following instrumentalities: Mounted below and in line with the vertical shaft 6 is a screw 38 threaded in a bush or sleeve 39 fast in the bed 4 before referred to. This screw carries at its upper end a collar 40, which collar is secured to the screw by means of a pin 41. The collar contacts with the under side of the pinion 9 before referred to, and forms a bearing for the lower end of the rotating shaft 6. The lower end of the screw 38 is provided with an operating disk 42 which is secured to the screw by means of a pin 43. There is also provided a lock nut 44 for holding the screw in adjusted position. It will be noted that the face of the gear 10 is somewhat wider than the face of the pinion 9. This is to provide for intermeshing of the two when the vertical shaft 6 is moved longitudinally to adjust the pasting mechanism vertically with respect to the cigarette rod forming mechanism. It is well known that in cigarette machines of the type to which the present invention is applicable, the cigarette rod forming mechanism occupies a position along the front of the machine. By reference to Fig. 2, it will be readily seen that the adjusting screw 38 is close to the front of the machine where it can be readily reached by the operator, and it will be readily understood that the screw may be operated and the vertical position of the pasting mechanism varied without stopping the machine. For the purpose of horizontally adjusting the paste applying wheel 23, and in fact the pasting mechanism as a whole, there is provided a limiting screw 45 projecting through the bracket 3 before referred to. This screw contacts with an arm 46, which arm is mounted upon a stud 47 fixed in the bracket 16 before referred to. It will be readily understood that by manipulating the screw 45, the horizontal position of the paste applying wheel 23 with respect to the upstanding side of the cigarette rod wrapper and with respect to the cigarette rod forming mechanism as a whole, may be varied without stopping the machine.

For the purpose of retaining the pasting mechanism in operative position when adjusted, there is provided locking means operative irrespective of the adjusted position of the pasting mechanism, and this means may vary in construction within wide limits. As shown, there is provided a shaft 48 suitably journaled in a bearing 49 formed on a bracket 50, which bracket is screwed or otherwise fastened to the bed 4 before referred to. One end of this shaft 48 is provided with an eccentric 51 which overlies and contacts with the arm 46 before referred to. The opposite end of the shaft 48 is pro-

vided with a handle 52 by means of which the eccentric is operated. The arm 46 is so shaped that the eccentric 51 may be thrown down to lock the arm at any adjusted position when the pasting mechanism

5 is in operative position. It is to be understood that although the means just described for adjusting the pasting mechanism is a convenient and effective 10 means for effecting the desired purpose, other mechanisms may be employed for this purpose if desired.

It is apparent that changes and variations 15 may be made in the structure by means of which the invention is carried into effect. The invention, therefore, is not to be restricted to the precise details of the structure shown and described.

What is claimed is:

20 1. The combination with a cigarette rod forming mechanism, of a rotating shaft, a pasting mechanism swingable on the shaft in and out of operative position, and means including the rotating shaft for driving the 25 pasting mechanism.

2. The combination with a cigarette rod forming mechanism, of a rotating shaft, a pasting mechanism swingable on the shaft in and out of operative position, means including the shaft for driving the pasting mechanism, and means for adjusting the pasting mechanism with respect to the cigarette rod forming mechanism.

3. The combination with a cigarette rod forming mechanism, of a rotating shaft, a pasting mechanism swingable on the shaft in and out of operative position, means including the shaft for driving the pasting mechanism, and means for adjusting the 40 pasting mechanism in two directions with respect to the cigarette rod forming mechanism.

4. The combination with a cigarette rod forming mechanism, of a rotating shaft, a pasting mechanism swingable on the shaft in and out of operative position, means including the shaft for driving the pasting mechanism, means for adjusting the pasting mechanism with respect to the cigarette rod 45 forming mechanism, and means for locking the pasting mechanism in adjusted position.

5. The combination with a cigarette rod forming mechanism, of a rotating shaft, a pasting mechanism swingable on the shaft in and out of operative position, means including the shaft for driving the pasting mechanism, means for adjusting the pasting mechanism in two directions with respect to the cigarette rod forming mechanism, and 50 means for locking the pasting mechanism in adjusted position.

6. The combination with a cigarette rod forming mechanism, of a vertical rotating shaft, a pasting mechanism swingable on the shaft in and out of operative position,

means including the shaft for driving the pasting mechanisms, and means for moving the shaft longitudinally to adjust the pasting mechanisms vertically with respect to the cigarette rod forming mechanism.

7. The combination with a cigarette rod forming mechanism, of a vertical rotating shaft, a pasting mechanism swingable on the shaft in and out of operative position, means including the shaft for driving the pasting mechanism, and a screw below and in line with the rotating shaft for moving the shaft longitudinally to adjust the pasting mechanism vertically with respect to the cigarette rod forming mechanism.

8. The combination with a cigarette rod forming mechanism, of a vertical rotating shaft, a pasting mechanism swingable on the shaft in and out of operative position, means including the shaft for driving the pasting mechanism, means for moving the shaft longitudinally to adjust the pasting mechanism vertically with respect to the cigarette rod forming mechanism, and a screw for adjusting the pasting mechanism horizontally with respect to the cigarette rod forming mechanism.

9. The combination with a cigarette rod forming mechanism, of a vertical rotating shaft, a bracket swingably supported on the shaft, a pasting mechanism carried by the bracket, means including the shaft for driving the pasting mechanism, and means for adjusting the bracket and pasting mechanism with respect to the cigarette rod forming mechanism.

10. The combination with a cigarette rod forming mechanism, of a vertical rotating shaft, a bracket swingably supported on the shaft, a pasting mechanism carried by the bracket, means including the shaft for driving the pasting mechanism, means for adjusting the bracket and pasting mechanism with respect to the cigarette rod forming mechanism, and means for locking the bracket and pasting mechanism in adjusted position.

11. The combination with a cigarette rod forming mechanism, of a vertical rotating shaft, a bracket swingably mounted upon the shaft, a pasting mechanism carried by the bracket, means including the shaft for driving the pasting mechanism, means for moving the shaft vertically to adjust the bracket and pasting mechanism vertically with respect to the cigarette rod forming mechanism, means for adjusting the bracket and pasting mechanism horizontally with respect to the cigarette rod forming mechanism, and means for locking the bracket and pasting mechanism in adjusted position.

12. The combination with a cigarette rod forming mechanism, of a vertical rotating shaft, a bracket swingably mounted upon the shaft, a pasting mechanism carried by

the bracket, means including the shaft and an independent belt and pulley for driving the pasting mechanism, means for moving the shaft longitudinally to adjust the pasting mechanism vertically with respect to the cigarette rod forming mechanism, and means for locking the pasting mechanism in adjusted position.

In testimony whereof, I have signed my name to this specification in the presence of 10 two subscribing witnesses.

ELBERON D. SMITH.
